AEROPLANE CONTROL

Filed July 11, 1929

UNITED STATES PATENT OFFICE

OTTO ADOLPHE SCHAEER, OF LUSANNE, SWITZERLAND

AEROPLANE CONTROL

Application filed July 11, 1929, Serial No. 377,449, and in Switzerland August 29, 1928.

The present invention relates to aeroplane controls and, more especially, to those of the type suitable for use in instructing new pilots.

The system of double joy-stick control now in common use in aviation schools are generally arranged so as to permit the teacher to throw out of action the joy-stick being manipulated by the pupil and to substitute his own when the occasion appears desirable or necessary. But in double joy-controls of this kind, it has hitherto been impossible during flight to again reverse control so as to permit the pupil to regain control of his joy-stick, a landing operation being first required to make the necessary readjustments.

One of the objects of the present invention is to provide a system of dual joy-stick control permitting one of two pilots to repeatedly throw either one of two joy-sticks into or out of action during flight.

Other objects will appear in the course of the detailed description now to be given with reference to the accompanying drawings, in which:—

25 Fig. 1 is an elevation, partially in section of one illustrative embodiment of the invention;

Fig. 2 is a plan, partially in section of the structure represented in Fig. 1;

30 Fig. 3 is a side elevation of the same device;

Figs. 4 and 5 are sections taken at right angles to one another of a second form of the invention;

Fig. 6 represents a third constructive modification; and

Fig. 7 illustrates a fourth possible embodiment of the invention.

Referring to Figs. 1 to 3 of the drawings, there is shown a joy-stick assembly composed of a tube 1 pivotally mounted at 3 on a forked element 2, journalled at 4 in fixed support 5, element 2 controlling the displacement of the altitude rudder,—a rubber or equivalent, flexible tube 6 attached at opposite extremities by collars 8 and 9 to tube 1 and to a rigid handle 7, having a recess 10 formed therein, a tube 12 terminating in a tapered portion 11, adapted to slide inside tubes 1 and 6,—and a pair of cables 13, 14 extending to the teacher-pilot's position, cable 13 passing over pulley

17 and terminating at 15 near the upper part of tube 12, and cable 14 passing over pulley 18, mounted on shaft 19, and terminating at 16 near the bottom of tube 12.

The operation of the device is very simple. Assuming that the student pilot manipulating handle 7 commits some error, the teacher-pilot pulls on cable 13 so as displace tube 12 downward thus breaking the rigid connection between elements 7 and 1 (position shown in Figs. 1 and 3). As soon as the teacher pilot deems it desirable to pass control back to the student, he pulls on cable 14, tube 12 moves upward and "rigidifies" flexible tube 6 by the interengagement of elements 10 and 11, and the student may thenceforth reassume full control. Flexible element 6 thus functions to break operative connection between elements 1 and 7 and permits the teacher to suspend the piloting function of the pupil at will.

In the modification shown in Figs. 4 and 5, the rigid connection between the control handle and the pivotally mounted tube is broken by raising (instead of lowering, as in Figs. 1 to 3) a central "rigidifying" tube. Here, the elements corresponding to those shown in Figs. 1 to 3 bear the same numerals and are primed. Tube 1¹ terminates at its upper extremity in a flared portion and is adapted to receive a pair of tubes 24 and 26, articulating universally at 25. Manipulating handle 21, 22 is connected to tube 1¹ by means of a rubber tube 23. When cable 14 is pulled in the direction of arrow 27, tubes 24 and 26 slide upward until universal joint 25 lies inside flexible portion 23. The pupil-pilot is then no longer able to control tube 1¹. When traction is exerted on cable 13¹ so as to lower tubes 24, 26 to the position shown in Figs. 4 and 5, rigid connection is reestablished between elements 1¹ and 21 and the pupil is again able to control his joy-stick.

In the modification shown in Fig. 6, a handle 28, traverses tube 1¹¹ similar to tube 1 of Figs. 1 to 3, and the student's control of the joy-stick is suspended by merely drawing handle 28 down into tube 1¹¹ by any con-

venient type of lever, or cable, or hydraulic control.

In the variant represented in Fig. 7, the general assembly is similar to the one shown in Figs. 1 and 3, except that elements 6, 7 and 12 controlling the rigidity of the joy-stick, are replaced by an assembly composed of tube 1¹¹¹ (similar to tube 1 of Fig. 1),—a plurality of interfitting elements 29,—a handle 30,—and a cable 31. It will be readily seen that when traction is exerted on cable 31 by any convenient form of device, cable 31 acts on handle 30 to bring elements 29 into forced engagement with one another and with tube 1¹¹¹ so as to render the connection between elements 30 and 1¹¹¹ substantially rigid. When, on the contrary, cable 31 is slackened, elements 29 no longer maintain the rigidity of the joy-stick, and pressure on handle 30 will not be transmitted to tube 1¹¹¹.

Various structures are now in use for repeatedly suspending the control of the "direction" rudder being manipulated by a student-pilot during flight, this being relatively easy because of the comparatively infrequent modifications in the direction of the plane in the course of a flight. On the contrary, the joy-stick, controlling the "altitude" rudder, is almost constantly in action and the solution of the problem of throwing a first joy-stick into, and out of action during flight in synchronism with a second joy-stick, presents real difficulties. These latter, it is believed, are overcome by the various forms of the invention hereinabove described.

What is claimed to be novel is:—

1. In a joy-stick assembly, a rigid pivotally mounted lever, a rigid handle, a deformable element interposed between said lever and said handle and adapted to be rendered rigid, and means operative to render said deformable element rigid.

2. In a joy-stick assembly, a pivotally mounted tube, a handle, a hollow, flexible tube connecting said tube and handle, a rigid element slidably mounted inside said pivotally mounted and flexible tubes and adapted to engage with said handle, and means for slidably displacing said rigid element inside said tubes whereby said rigid element may establish a rigid connection between the pivotally mounted tube and the handle.

3. In a joy-stick assembly, a pivotally mounted tube, a hollow handle, a rubber tube connecting said tube and handle, a pivotally connected assembly mounted to slide in said pivotally mounted tube and including a rigid element adapted to slide in said rubber tube and to form a rigid connection between said pivotally mounted tube and hollow handle, and a tube pivotally connected to said rigid element, and means for moving said last named tube to displace said pivotally connected assembly in either direction.

4. In a joy-stick assembly, a rigid pivotally mounted lever, a handle, a flexible tube connecting the lever and the handle, and rigid means adapted to be passed through said tube to render the joy stick rigid.

5. In a joy-stick assembly, a pivotally mounted stick having a flexible portion intermediate the ends thereof, a second stick slidably mounted within said first stick and having a pivotal joint intermediate the ends thereof, and means for causing relative movement of said sticks so as to render the first stick rigid or non-rigid at will.

In testimony whereof I have signed this specification.

OTTO ADOLPHE SCHAER.
